INVENTOR:
John Hauenstein,
BY
F. G. Fischer,
ATTORNEY.

UNITED STATES PATENT OFFICE.

JOHN HAUENSTEIN, OF KANSAS CITY, MISSOURI.

COMBINATION MIRROR AND TELEPHONE MOUTHPIECE.

Application filed December 31, 1921. Serial No. 526,319.

To all whom it may concern:

Be it known that I, JOHN HAUENSTEIN, a citizen of the United States, residing at Kansas City, in the county of Jackson and 5 State of Missouri, have invented certain new and useful Improvements in Combination Mirrors and Telephone Mouthpieces, of which the following is a specification.

My invention relates to a new and useful 10 article of manufacture cooperatively combining a mirror and a sanitary screen, one side of which latter is protected by the mirror when adjusted to active position. The mirror may be used to advantage in 15 shaving or otherwise preparing the toilet, while the screen is adapted to be placed against or adjacent to the mouth-piece of a telephone while talking to prevent the transmission of disease germs either to or 20 from said mouthpiece.

The device is preferably made on a small scale, so that it may be readily carried either in a hand bag or a pocket and is of ornamental and inexpensive construction.

25 In order that the invention may be fully understood, reference will now be had to the accompanying drawing, in which:

Fig. 1 is an elevation of the device shown 30 fully open in solid lines and partly closed in dotted lines.

Fig. 2 is a cross section on line II of Fig. 1, showing the device folded.

Fig. 3 is a fragmentary section on line 35 III—III of Fig. 1.

Fig. 4 is a fragmentary section on line IV—IV of Fig. 1.

Fig. 5 is an elevation showing important 40 parts of the invention before being incorporated in the complete device.

In carrying out the invention, I provide 45 a disk 2 and an annulus 4, preferably, stamped from one piece of sheet metal or other suitable material and united by a connecting element 6. The inner margin of the annulus 4 is pressed outwardly to form 50 a circular flange 7 against the inner surface of which a mirror 8 is secured. Said mirror 8 may consist either of glass or a highly polished nickel plated metal disk having marginal recesses 9 to receive a small amount of solder, cement or other suitable material for firmly securing said disk to the flange 7.

55 10 designates another annulus, the inner margin of which is pressed outwardly to

form a circular flange 12 in which a screen 14 of tissue paper or other thin material is secured by a rubber or other suitable washer 15, cemented or otherwise secured to the flange 12 and said screen 14. The periphery of the annulus 10 is provided with oppositely disposed spring clips 16 and 18, for a purpose which will hereinafter appear.

In assembling the device the connecting element 6 is folded at its central portion to 60 bring the disk 2 and the annulus 4 into proximity with each other, as disclosed by Figs. 1 and 2, a sufficient space 19 being left to receive the annulus 10 which is operably secured in place by a pivot 20, the 65 ends of which hold the disk 2 and the annulus 4 against the intervening annulus 10 with sufficient friction to retain the same in its outward position, as disclosed by Fig. 1. When the annulus 10 is swung inwardly 70 to inactive position as disclosed by Fig. 2, the flange 12 is received by the saucer-shaped disk 2, while the clips 16 and 18, frictionally engage the disk 2 and the annulus 4, respectively.

The annulus 10 is provided adjacent to the washer 15 with an integral wedge 26, which, when said annulus is swung to inactive position, engages the disk 2 and prises it and the annulus 4 apart, so that the annulus 10 can readily enter the space 19.

When the annulus 10 is swung outwardly to active position it is retained in such position by frictional engagement of the disk 2 and annulus 4, and also by a small 85 indentation 22 on the annulus 4 which springs into a corresponding indentation in the annulus 10.

Having thus described my invention, what I claim and desire to secure by Letters Patent, is:

1. A portable device of the character described consisting of an annulus, a screen covering the opening in said annulus, a disk, a second annulus connected to and spaced from the disk to provide an opening to receive the first annulus, a mirror fixed to cover the opening in the second annulus and coacting therewith and the disk in protecting the screen when the first annulus is 100 swung inwardly between the second annulus and the disk, and a pivot on which said first annulus may be swung inwardly as stated, or outwardly from between the second annulus and the disk.

2. A device of the character described, consisting of two circular members spaced apart and united by a peripheral connection, an annulus mounted to swing between and be held in outward position by frictional engagement with said circular members, a screen covering the opening in said annulus, and clips on the annulus for engaging the two circular members to reliably secure said

annulus when swung inward between the 10 two circular members.

In testimony whereof I affix my signature in the presence of two witnesses.

JOHN HAUENSTEIN.
